Application April 5, 1935, Serial No. 14,736

8 Claims. (Cl. 170—149)

This invention relates to improvements in propellers and more particularly to propellers adapted for use on airplanes although it is capable of other uses. One object is to provide a propeller 5 capable of operation with little air resistance. A further object is to provide a propeller of a reciprocating type having a working stroke and an idle stroke, automatically operative means being provided for adjusting the propeller broad-side to the wind during its working stroke and edgewise to the wind during its idle stroke.

A further object is to provide a propeller that is positive and efficient in operation and durable in use. With the foregoing and other objects 15 in view the invention consists in the combination and arrangement of parts to be hereinafter fully described, pointed out in the claims and illustrated in the drawings which form a part of this application for patent and in which—

Fig. 1 is a side view of one form of the propeller, one pair of blades being shown partly broken away.

Fig. 2 is a cross sectional view taken on the line 2—2 of Fig. 1.

Fig. 3 is a cross sectional view taken on the line 3—3 of Fig. 1.

Fig. 4 is a longitudinal sectional view taken on the line 4—4 of Fig. 1.

Fig. 5 is a detail view, partly in section, showing one end of the spirally grooved propeller shaft, taken on the line 5—5 of Fig. 6.

Fig. 6 is a fragmentary sectional view showing the spirally grooved propeller shaft and the shoe travelling therein.

Fig. 7 is a fragmentary plan view of a modified form of the propeller illustrating the blade-turning mechanism arranged at one end of the housing.

Fig. 8 is a view of Fig. 7, in side elevation, taken on the line 8—8 thereof.

Fig. 9 is a view of Fig. 8 with the adjustable parts in an altered position.

Fig. 10 is a view of Fig. 7 with the adjustable parts in an altered position.

Fig. 11 is a fragmentary plan view similar to Fig. 7, at the beginning of a stroke.

Fig. 12 is a cross sectional view taken on the line 12—12 of Fig. 11.

Fig. 13 is a cross sectional view of Fig. 12 with the adjustable parts in an altered position, and it is taken on the line 13—13 of Fig. 14.

Fig. 14 is a view of Fig. 11 with the adjustable parts in an altered position.

Fig. 15 is a fragmentary sectional view taken on the line 15—15 of Fig. 14.

Fig. 16 is a fragmentary sectional view taken on the line 16—16 of Fig. 10.

Fig. 17 is a fragmentary side view of the propeller showing the application of the blade-turning mechanism.

Fig. 18 is an enlarged fragmentary view of a further modified form of the propeller, the blades being now in wind-cutting position.

Fig. 19 is a view of the blades, broken, in elevation.

Fig. 20 is a sectional view taken on the line 20—20 of Fig. 18.

Fig. 21 is a fragmentary sectional view, enlarged, taken on the line 21—21 of Fig. 18.

Like reference characters denote corresponding parts throughout the several views.

The present propeller includes a cylindrical housing secured to the forward end of the airplane, or vehicle, and enclosing a rotary engine-driven spirally grooved propeller shaft to which the propeller blades are secured for reciprocation, one type of blade being adapted to rotate at the end of each stroke. Secured to the forward end 1 of the airplane by bolts 2 is the cylindrical housing 3 having the outer end 4 closed and tapered to offer the least wind resistance.

Referring now to Figs. 1 to 6, inclusive, of the drawings, the housing 3 is formed with four slots 5 spaced ninety degrees apart and extending longitudinally thereof, the ends of said slots being 30 spaced from the ends of the housing. Arranged within the housing are bearings 6 adapted to receive the disc-like ends 7 of the rotary shaft 8 that is fast to the propeller shaft 10 and that is formed with spiral grooves 11 running from end 35 to end thereof back and forth, said spiral grooves 11 terminating at each end, illustrated in Fig. 5, in the return groove 11a so that a shoe travelling from one end of a spiral groove 11 to the other end will be caused to return again, thus providing a 40 continuous back and forth movement.

Mounted in the slots 5 are the propeller blades, four in number, arranged in pairs, the members of each pair being disposed diametrically opposite each other, each blade having a shaft portion 12 that connects its head 13 to its heel portion 14 which fits snugly, dove-tail fashion, in the slot 5 and is perforated to receive and retain the hollow threaded screw 15 that receives the head of the shoe 16 that runs in the spiral grooves 11, the inner end or head of the shoe being engaged by an expansion coil spring 17 within the screw so that the tension upon the shoe can be manually adjusted by adjustment of the screw. The head 13 of the blade is arrow-shaped in cross 55

section so that as it moves in one direction, the idle stroke, away from the airplane it cuts the wind offering the least wind resistance and as it moves in the opposite direction, the work stroke, toward the propeller its broad but somewhat concave face is presented to the wind. The tread or tongue portion of each shoe that rides in the groove 11 is of greater length than the point of intersection, or cross-over point, of the grooves so that a shoe will not ride out of one groove 11 into the opposite groove at any point of intersection. Rotation of the motor shaft 10 rotates the shaft 8 and causes the blades to ride back and forth in the slots 5 as the shoes 16 ride from end to end of the shaft 8 in the spiral grooves 11. The work strokes of the blades are those strokes toward the airplane from the outer or beveled portion of the housing.

Referring now to Figs. 7 to 17 inclusive, a modified form of the invention is illustrated. The housing 3 is formed with longitudinally extending slots 5 in which the head blocks 18 are slidably arranged, lateral flanges of said blocks being disposed in offset portions of the slots, said head blocks being recessed to snugly receive the rounded ends 19 of the blades 20, the shafts 21 thereof extending snugly through perforations in said head blocks, the blades proper rising above the housing 3 being of concavo-convex formation so that during the working strokes of the blades their concave faces are presented to the wind and during their idle strokes the blades are presented edgewise to the wind, automatic blade-positioning mechanism being provided for engagement with the blades at each end of a stroke. Each blade includes a shaft 21 that runs from the blade proper to a heel portion 14 provided with a shoe 16 running in the spiral grooves 11.

As the blades move from the outer free end of the housing 3 toward the airplane the blades 20 are presented broadside to the wind in a power stroke. When the blades reach the inner end of this stroke they each encounter blade-positioning mechanism. Each rounded end 19 of each blade is formed with two spaced recesses 22, 23, ninety degrees apart, said recesses being adapted alternately for alignment with a perforation 24 in the head 18 to releasably carry a cross-shaped pin 25 yieldingly retained in position in either recess 22, 23 by means of a spring 26 disposed in an enlarged portion of the perforation 24. While the pin 25 connects the end 19 of the blade proper with the head 18 the said end 19 cannot oscillate but when said pin is removed from the end 19, but retained by the head 18, the blade proper may oscillate independently of said head. Secured to a block 27 supported inside the housing is a spring 28 having its forward or free end bent slightly and bifurcated to form the prongs 29, the inner end of the bifurcation terminating in a slightly enlarged perforation 30, the space between the forks being smaller than the head of the pin 25, the perforation 30 being at a point in line with the pin 25, and with the perforation 24 in the head block 21 at the inner end of the work stroke of the blade.

A bolt 31 supported in guides 32 upon the housing is encircled, between said guides, by an expansion coil spring 33 and connected to one end of the same so that the bolt is normally or yieldingly retained in a predetermined position with its free end in the path of the blade so that contact therewith is had as the blade completes its work stroke. The downwardly curved and bifurcated end of the spring 28 disposed in the path

of movement of the pin 25 receives the same between its prongs. The outer curvature of said spring causes it to lift the pin, by its head, out of the recess 22 in the blade end 19 just previous to contact of that blade with the bolt 31. Contact of the blade with the said bolt will oscillate the blade into a position at right angles to its stroke position and edgewise to the wind. As soon as the blade is positioned edgewise to its path of movement the recess 23 is disposed opposite the pin 25, the inner end of which will then be forced into said recess by the spring 26.

The blade, edgewise to the wind, now moves toward the outer end of the housing 3 and when at the end of this idle stroke it encounters another spring 28 that lifts its pin 25 out of the recess 23, as previously described with relation to the recess 22, and encounters the beveled end of a pawl 34 pivotally secured to a boss 35 carried by the housing 3, said pawl being pressed toward the blade 20 by a spring 36 that provides sufficient resiliency to compensate for the sharp contact between the blade and the pawl, this contact serving to reposition the blade broadside to the wind for the return or work stroke, the pin 25 now being deposited again in the recess 22 to hold the blade in this adjusted position. In this manner the blade will be positioned broadside to the wind for each work stroke and edgewise to the wind for each idle stroke.

Referring now to Figs. 18 to 21 inclusive the housing 3 is formed with relatively large slots 5 to receive the relatively large head blocks 18a that are formed each with an enlarged recess to receive the pinion heads 19a of the twin blades 20a.

The shanks of the wings 20a extend through perforations 37 in the head block, said pinion heads being in mesh, said blades 20a having their upper portions inclined at an angle to provide clearance when they make a quarter turn at the end of each stroke to begin the return stroke. One pinion head 19a of each pair of blades 20a is formed with recesses 22, 23 to receive the inner end of the pin 25. The positioning movement of one blade 20a is identical with that described for a blade 20 and the one blade 20a instantly imparts movement, through the meshed pinion heads to its companion blade. The area of a twin blade being greater than that of a single blade 20 the twin is capable of delivering greater power in operation.

What is claimed is:—

1. In propellers, a housing, a rotary spirally grooved shaft associated with said housing, and reciprocating blades mounted to said housing and operatively connected to said grooved shaft.

2. In propellers, a housing, a rotary spirally grooved shaft associated with said housing, reciprocating blades mounted to said housing and operatively connected to said grooved shaft, and means for automatically positioning said blades broadside to the wind during one stroke and edgewise to the wind during the opposite stroke.

3. In propellers, a slotted housing, a rotary spirally grooved shaft mounted within said housing, reciprocating blades mounted to said housing for operation in the grooved portions thereof, and connection between said blades and the said grooved shaft.

4. In propellers, a slotted cylindrical housing, the slots thereof being disposed ninety degrees apart and extending longitudinally thereof, pairs of reciprocating blades mounted in said housing slots, the members of each pair being disposed

diametrically opposite each other, a rotary spirally grooved shaft mounted in said housing, and connection between said blades and said spirally grooved shaft.

5. In propellers, a slotted cylindrical housing, reciprocating blades mounted in pairs in said slots, blade positioning means arranged at the ends of said housing slots operable at the end of each blade stroke, a rotary spirally grooved shaft within said housing, and connection between said blades and shaft.

10. In propellers, a slotted cylindrical housing, reciprocating blades mounted in pairs in said slots, blade positioning means arranged at the ends of said housing slots operable at the end of each blade stroke upon the members of each pair of blades simultaneously, a rotary spirally grooved shaft within said housing, and connection between said pairs of blades and said shaft.

15. In propellers, a slotted cylindrical housing, head blocks slidable in said slots, blades adjust-

ably mounted in said head blocks and including recessed rounded end portions, pins adjustably carried by said head blocks for removable disposition in the recesses in said rounded end portions, resilient pin adjusting means carried by said housing at the ends of its slots automatically operative at the end of each blade stroke whereby said pins are moved from one to the other of said rounded-end recesses, blade adjustment means at the ends of said housing slots operative at the end of each blade stroke, a rotary spirally grooved shaft within said housing, and connection between said shaft and said blades.

20. In propellers, a slotted cylindrical housing, a rotary spirally grooved shaft within said housing, reciprocating blades mounted to said housing for operation in the grooved portions thereof in pairs, and connection between said blades and shaft.

PEDER PEDERSEN. 20
